Primary Examiner — Jasmine Mlinarcik*Assistant Examiner* — James P McKane(74) Attorney, Agent, or Firm — Jeenam Park(57) CLAIM

The ornamental design for a shawl, as shown and described.

DESCRIPTION

FIG. 1 is a perspective view of a shawl showing our new design;

FIG. 2 is a front view thereof;

FIG. 3 is a rear view thereof;

FIG. 4 is a perspective view of the shawl as worn by the user in a first configuration of use;

FIG. 5 is a perspective view of the shawl as worn by the user in a second configuration of use;

FIG. 6 is a perspective view of the shawl as worn by the user in a third configuration of use; and,

FIG. 7 is a perspective view of the shawl as worn by the user in a fourth configuration of use.

The broken line outline of the partial human mannequin figure in FIGS. 4-7 assists in illustrating the shawl in a position of use, but forms no part of the claimed design.
